UNITED STATES PATENT OFFICE.

PAUL J. KAVENEY, OF BLOOMINGTON, ILLINOIS.

ANGLE-COCK AND ACTUATING MEANS THEREFOR.

1,349,208.

Specification of Letters Patent. Patented Aug. 10, 1920.

Application filed January 21, 1920. Serial No. 353,053.

To all whom it may concern:

Be it known that I, PAUL J. KAVENEY, a citizen of the United States, and a resident of Bloomington, in the county of McLean 5 and State of Illinois, have invented certain new and useful Improvements in Angle-Cocks and Actuating Means Therefor; and I do hereby declare that the following is a full, clear, and exact description thereof, 10 reference being had to the accompanying drawings, and to the characters of reference marked thereon, which form a part of this specification.

This invention relates to improvements in 15 angle cocks for use on railroad trains that are located at the ends of the cars and in the train lines (steam or air) for conveying the material from one car to another car coupled thereto through the usual flexible 20 hose and angle cock connections, and the invention refers more specifically to improvements in means for operating angle cocks themselves from the sides of the cars, so that it is unnecessary for the trainmen to 25 enter between the cars to operate the angle cock to cut off the material passing therethrough, and refers also to a novel form of angle cock to adapt it to such operating mechanism.

30 The purpose of the invention is to provide a construction of this character which renders it unnecessary for the trainmen to go between the cars to operate the angle cock when coupling and uncoupling cars and 35 when adjusting the air or steam connections between the cars. In respect of this phase of the invention it embraces novel actuating means, as bars, rods, or the like, which are connected at their inner ends to the moving 40 part of the angle cock and extend at their outer ends to about the planes of the sides of the car, each car having two of said operating mechanisms or handles extending in opposite directions from the angle cock to 45 the opposite sides of the car.

Another object of the invention is to provide a novel actuating device, as the hand piece or bar, and a novel means of connecting it to the moving part of the angle cock, 50 so that the device as a whole may be adapted to standard cars, while avoiding clashing of the operating devices with other equipments at the end of the car, such as the coupler heads, draw bars, and the like.

55 Another object of the invention is to provide, in combination with such means for

operating the angle cock, a novel form of the structure of the angle cock which avoids the presence of any projection of the operative part of the angle cock above the plane 60 of the general structure such as is liable to interfere with the passage of a trainman between coupled cars, or such as may result in the operative part of the cock being opened or closed by the foot of the trainman 65 while passing between the cars.

The invention consists in the combination and arrangement of the parts shown in the drawings and described in the specification, and as pointed out in the appended claims. 70

In the drawings:

Figure 1 is a partial plan view of two adjacent cars coupled together showing my improvements applied thereto.

Fig. 2 is an end view of a car showing the 75 improvements as seen when looking at the end of the car.

Fig. 3 is a partial plan and partial sectional view of the angle cock.

Fig. 4 is a side view of the angle cock. 80

It will be understood that my improvements are adapted to all types of cars, and the cars herein shown are diagrammatically illustrated to show the manner of the application of the invention thereto without restriction, however, to the particular manner in which the operative parts of my improvements may be applied to any given car. 85

As shown in said drawings, 10, 10 designate the adjacent ends of two cars; 11, 11 90 the coupling knuckles, and 12, 12 the draw bars connected to the frame structure and the end sills in any known or preferred manner. In the following description it will be assumed that my invention is adapted to the 95 angle cocks that are connected in the air line for the air-brake system of the train and will be so described, without limitation, however, to the particular material which the angle cocks are designed to control. 100

14, 14 designate the angle cocks at the adjacent ends of two coupled cars. Each of said angle cocks is connected at its inner end to the train line pipe 15 by the nipple 16 in the usual manner, whereby said angle 105 cocks are rigidly connected to the train pipes. At the other or inner ends of the angle cocks are nipples 17 to which are connected the flexible hose sections 18, which latter drop below the coupler heads and are connected at their free ends by the usual hose coupling not herein shown. 110

The construction of the valve is shown most clearly in Figs. 3 and 4. The valve casing 20 comprises a chambered casting of suitable shape which is formed with a 5 through chamber 21 in free communication with the nipples 16 and 17 and the train pipes and flexible coupling sections. The said casing is provided between its ends with registering openings 22, in which is seated 10 a cross bushing 23, said bushing extending at its ends a distance beyond the sides of the valve casing and into nipples 24 made integral with the side walls of the casing. Said bushing is provided inside the chamber 21 with oppositely arranged elongated ports 25 which are preferably disposed in the horizontal plane of the valve so that, when the valve is open through these ports, air passes directly through the valve chamber. 26 designates a rocking valve which fits closely within the bushing 23 and extends from end to end thereof. Said valve is provided with oppositely disposed elongated ports 27 which, when the cock is closed, are 20 out of line with the ports 25 but, upon rocking said valve 26 ninety degrees in either direction, the ports 27 and 25 are brought into register to open the valve. 28 designates shanks or stems extending endwise from the 25 valve piece. Said valve stems extend through nuts 29, the flanges 30 of which are interiorly threaded to overlap and be screw threaded on exterior screw threads of the nipples or necks 24 of the casing. The nuts are provided with axial, outwardly opening chambers to receive packings 31 and threaded glands 32, which are threaded into end extensions of the nuts to press the packing against the stems 28 and thereby prevent 35 leakage of material outwardly past said stems. Said stems are provided with polygonal terminals 33 for connection to the operating device hereinafter described. A packing washer 34 is interposed between the 40 bottoms of the chambers in said nuts, surrounded by the flanges 30, and the ends of the nipples 24 and the shoulder portions 35 between the valve piece and the stems so as to avoid leakage of the material past the 45 valve piece and between the same and the bushing.

In order to limit the movement of the valve piece in both its opening and closing positions, the following stop mechanism is 50 provided. The said nuts are provided with stops 36 of any suitable form which project radially therefrom, or said stops, if desired, may be fixed to the casing. 37, 37 designate yokes, each having two arms 38, the middle 55 portions of the yokes being formed with squared openings to fit non-rotatively over the squared terminals 33 of the stems 28. The said arms 38 of said yokes extend inwardly over the nut 29, which latter is made 60 exteriorly cylindric, so that said stops 36 are

in the paths of the arms 38 of the yokes and limit rocking movement of the yokes which, by reason of their nonrotative connection with the stems 28 of the valve piece, similarly limits rocking movement of the valve 70 piece.

Referring now to the operating means for rocking the valve piece of the angle cock, the same are made as follows:

40, 41 designate operating bars which are 75 loosely connected at their inner ends to the stems 28 of the valve piece and are directed outwardly toward the sides of the car and may be there supported by any suitable form of hanger 42 attached to the car structure, the ends of the bars terminating in hand piece 43. It will be noted by reference to Figs. 1 and 2 of the drawings that the angle cock of each car is located at one side of the draw bar and above the plane of 80 the lower side of the bar, the angle cock of one car being on one side of the car draw bar and the angle cock of the adjacent car being at the other side of its draw bar, as usual, with the flexible hose drooping obliquely across and beneath the coupling knuckles. For this reason, one of the operating bars, the operating bar 40, extends from its associated angle cock beneath the adjacent draw bar to its side hook 42. It 85 thereby becomes desirable, in order to bring the outer end of the operating bar 40 to a convenient suspending position at the hook 42 to curve said bar 40 at 44, where it passes beneath the draw bar and thence incline it 90 upwardly to its suspending hook. It is also desirable that the other, or shorter, operating bar be inclined upwardly from its point of connection to the valve piece to its suspending hook. In order to accommodate 95 said operating bars to the conditions described, the inner ends of said bars are connected to the opposite ends of the stems of the valve controlled thereby by joints which permit the operating bars to be rocked to 100 open and close the angle cocks regardless of the angle and curvature of the operating bars. The said flexible joints each consist, as best shown in Fig. 3, of a fitting 46 that has a squared socket to fit over the adjacent 105 squared terminal of the valve piece stem and is fixed thereto in any suitable manner, as by means of a set screw 47. Said fitting is forked to receive a rocking member 48 which, in turn, is pivotally connected between the arms of a second fitting 49; as by 110 means of a pivot pin 50. The outer end of the socket fitting 49 has an angular socket to receive the inner squared end of the operating bar, and said operating bar may be 115 attached thereto by the bolt 51, shown in said Fig. 3. With this construction and arrangement, it will be observed that the outer ends of the operating bars 40 and 41 120 may be elevated at any suitable angle for 125 130

suspending connection to the car body frame adjacent to the sides of the car and that the knuckle or universal joints formed by the parts 46, 48, and 49 will transmit rocking movement to the valve piece, regardless of the angles of the operating bars.

An advantage of the construction described is that each angle cock at the end of the car is provided with two operating rods 10 that extend adjacent to the sides of the car so as to be accessible to a trainman standing at the sides of the car and thereby avoids the necessity of the trainman entering between the car to open and close the angle cock. It will be further noted that the two angle cocks of adjacent coupled cars may be operated from either side of the car by a single trainman, thus avoiding the necessity of the trainman passing therebetween or 20 over the coupling connections.

It has been found in practice that where the operating handle or device of the angle cock is located at the upper side of the angle cock it not only exposes the trainman to danger in reaching the operating device for opening and closing the angle cock, but also presents an upward projection from the body thereof, which is liable to be struck by the foot of a trainman passing between the 30 cars and over the coupling or draw heads. This may result in either of two adverse conditions; first, the trainman may catch the bottom of his trousers on the actuating device so that he may trip and fall under the 35 car, thus endangering his life, or contact of his foot with the actuating device may accidentally open or close the same inadvertently. If the angle cock be connected to an air train line, the condition of the brakes 40 may be maladjusted, with the attendant difficulty of locating the point in the train where such maladjustment occurs, thereby entailing trouble and delay in starting the train.

45 It will be understood that the structural details of the illustrative embodiment of the invention may be varied within the scope of the claims hereto appended and that the invention is not limited to the structure shown 50 except as to claims wherein the structure is specifically set forth and as imposed by the prior art.

I claim as my invention:

1. An angle cock and actuating means 55 therefor for use on railway cars, comprising in combination with an angle cock, embracing a casing and a closure member provided with horizontal, oppositely disposed stems, actuating devices connected at their 60 inner ends to said closure member stems and extending outwardly therefrom, and means at the sides of the car to support said actuating devices.

2. An angle cock and actuating means 65 therefor for use on railway cars, comprising,

in combination with an angle cock at one side and above the plane of the lowest part of the car draw bar, said angle cock having a horizontal rocking closure member provided below the plane of the top of the 70 angle cock with oppositely extending stems, actuating bars connected at their inner ends to said closure member stems and extending outwardly therefrom to the car side, and means to support the outer ends of said bars, 75 one of said bars being curved between its ends to pass the draw bar.

3. An angle cock and actuating means therefor for use on railway cars, comprising, in combination with an angle cock, embracing 80 a casing and a closure member provided with horizontal, oppositely disposed stems, actuating bars connected at their inner ends to said stems by knuckle joints, and means at the sides of the car ends to support the 85 outer ends of said bars.

4. An angle cock and actuating means therefor for use on railway cars, comprising, in combination with an angle cock, embracing 90 a casing and a closure member provided with horizontal, oppositely disposed stems, actuating bars for said closure member, having means to support the outer ends thereof at the sides of the car end, and knuckled fittings at the inner ends of said bars having 95 non-rotative connection to said bars and to said stems.

5. An angle cock and actuating means therefor for use on railway cars, comprising, in combination with an angle cock, embracing 100 a casing having means to connect it to a train pipe and to a hose coupling and provided with a transverse, horizontal ported member, a ported rocking closure in said ported member, and having stems extending 105 oppositely therefrom, actuating bars connected at their inner ends to said valve stems by joints permitting the closure to be actuated by the actuating bars when occupying different angles with reference to the 110 axis of said closure, means at the car end sides for supporting the outer ends of said bars, and stop devices on the stems and said casing to limit the rocking movement of the closure.

6. An angle cock and actuating means therefor for use on railway cars, comprising, in combination with an angle cock, embracing 120 a casing and a closure member provided with horizontal, oppositely disposed stems, actuating devices connected at their inner ends to said closure member stems and extending outwardly therefrom, means at the sides of the car end to support 125 said actuating devices, yoke members connected to and rotative with said stems, and stops on the casing adapted to limit angular movement of the arms of said yoke, and thereby limit the operating movement of said closure member.

7. An angle cock and actuating means therefor for use on railway cars, comprising, in combination with an angle cock, embracing a casing and a rocking closure member 5 therein and having stems which extend through and beyond packing joints at the sides of the casing, rocking actuating bars connected to said stems and extending outwardly away therefrom, with means for supporting the outer ends of said bars at the sides of the car structure.

8. An angle cock and actuating means therefor for use on railway cars comprising a casing having a transverse, horizontal

ported bushing therein, a ported rocking 15 valve member in said bushing having horizontal stems that extend through and beyond opposite side walls of said casing, actuating bars for said valve member connected at their inner ends to said stems and 20 extending oppositely therefrom to the car sides, and means to support the outer ends of said actuating bars from the car structure.

In witness whereof I claim the foregoing as my invention, and hereunto append my signature this 19th day of January, 1920.

PAUL J. KAVENEY.
